UNITED STATES PATENT OFFICE.

HARRY E. JENKINS, OF JOPLIN, MISSOURI, ASSIGNOR OF ONE-HALF TO GEORGE H. GLADE, OF JOPLIN, MISSOURI.

HOISTING MECHANISM.

1,192,322

Specification of Letters Patent. Patented July 25, 1916.

Application filed September 27, 1915. Serial No. 52,928.

To all whom it may concern:

Be it known that I, HARRY E. JENKINS, citizen of the United States, residing at Joplin, in the county of Jasper and State of Missouri, have invented certain new and useful Improvements in Hoisting Mechanism, of which the following is a specification.

My invention relates to improvements in hoisting mechanism, adapted to be driven by an electric motor, or any other source of power, suitable for use in mines or the like, while not necessarily restricted to such use.

The recent application of the electric motor as a prime mover for hoisting mechanism, employed in mines or the like, has created a demand for a drum embodied in such hoisting mechanism, which will, upon starting, wind up or move the cable slowly, without jerks, and quickly accelerate the movement of the cable until the maximum speed is reached. I am aware that attempts have heretofore been made to accomplish this result, but these have not generally proven satisfactory. For instance, it has been proposed to employ a stepped cone-shaped drum for this purpose. The disadvantages of the cone-shaped drum are numerous, among which may be mentioned the fact that the movement of the cable is gradually accelerated from the minimum to the maximum circumferences of the cone, the intermediate circumference determining the average speed of the upward travel of the cable, and the maximum velocity of the cable being reached only when the can, bucket, or the like has reached the end of its travel and must be stopped. A further disadvantage of this cone-shaped drum is that it can receive only a single layer of cable, and for shafts of considerable depth, the drum would have to be extraordinarily large and unwieldy, to hold sufficient cable to meet the requirements.

I have discovered that if the drum of the hoisting mechanism is provided at one end with a groove or slot, inclined inwardly with respect to the longitudinal axis of the drum, and in the direction of the sheave or pulley over which the cable passes the friction between the cable and the adjacent end or edge of the drum would be reduced to the minimum, and highly satisfactory results obtainable.

The invention also consists of improved

brake mechanism for controlling the rotation of the drum. Means are provided for holding a section of surplus cable upon one end of the drum adjacent the groove, and for permitting of such surplus cable being fed into the groove, when it is necessary to cut off the end of the cable connected with the can, bucket or the like, where the cable ordinarily wears out first.

An important object of the invention is to provide a machine of the above mentioned character, which is simple in construction, inexpensive to manufacture, and reliable in operation.

Other objects and advantages of the invention will be apparent during the course of the following description.

In the accompanying drawings forming a part of this specification and in which like numerals are employed to designate like parts throughout the same, Figure 1 is a side elevation of hoisting mechanism embodying the invention, Fig. 2 is a central vertical longitudinal sectional view through the hoisting drum, Fig. 3 is an end elevation of the drum, Fig. 4 is a similar view of the opposite end, Fig. 5 is a transverse sectional view taken on the line 5-5 of Fig. 2, Fig. 6 is a detailed section taken on line 6-6 of Fig. 3, Fig. 7 is a plan view of the drum and sheave or pulley, and, Fig. 8 is a detailed section through the clamp.

In the drawings, wherein for the purpose of illustration is shown a preferred embodiment of my invention, the numeral 10 designates a base of the hoisting mechanism, as a whole, upon which is suitably mounted an electric motor 11, having an armature shaft 12. This armature shaft is connected, by means of a coupling 13, with a shaft 14 of the hoisting mechanism. This shaft is journaled through stationary bearings 15, as shown.

Mounted upon the shaft 14 is a cylindrical drum 16, embodying ends or heads 17 and 18, having hubs 19, mounted upon the shaft 14. The cylindrical drum 16 is to be revolved by an expanding or contracting clutch, or any other approved means to lock it to the shaft 14, but not shown. These ends or heads 17 and 18 are provided with flanges 20, extending outwardly beyond the drum 16 for a substantial distance, as shown.

The end or head 18 is provided with an annular groove 21, which is inclined in

wardly with respect to the longitudinal axis of the drum 16, and toward a sheave or pulley 21' (Fig. 7) spaced a substantial distance from the drum, and over which the 5 cable passes prior to its connection with the can. The inward inclination of the annular groove 21 will depend upon the distance that the pulley or sheave is from the drum and the length of the drum.

10 The numeral 22 designates a cable, which operates within the groove 21, and is passed through an angularly arranged opening 23, as shown in Fig. 6. This cable passes to the exterior of the end or head 18 and is held thereto by means of a clamping plate 24, attached to the head 18 by means of bolts 25 or the like. This cable 22 extends upon the outer side of the head 18, as surplus cable, and is rolled or coiled in a space 26, afforded 20 by a flange 27, and held in the space by strips 28, detachably connected with the head 18 by bolts 29 or the like.

As more clearly shown in Fig. 5, the numeral 30 designates an equalizing wedge, 25 rigidly mounted within the bottom of the groove 21 and having its large end disposed adjacent the opening 23 through which the cable passes, such wedge tapering away from such opening. The large end of the wedge 30 is of substantially the thickness of the cable, whereby the next turn of the cable will pass over the first turn without forming a pronounced hump.

As clearly shown in Figs. 2 and 4, the 35 numeral 31 designates a supporting rail or member, surrounding the adjacent flange 20 and held stationary with relation thereto. This supporting rail is apertured at suitably spaced intervals for receiving reciprocating 40 hooks 32, moved outwardly by coil springs 33, the tension of which may be regulated by adjusting the nuts 34. The inner ends of these hooks engage with co-acting hooks 35, attached to a brake-band 36, having a suitable lining 37, operating in a groove 38 formed in the adjacent annular flange 20. One end of this brake-band, as clearly shown in Fig. 4, is connected with a stationary rod 39, while its opposite end is pivotally connected with a vertically swinging crank 40 rigidly mounted upon a rock-shaft 41. This rock-shaft is adapted to be operated by means of a lever 42 or the like. The function of the hooks 32 and associated elements 45 is to provide means for holding the brake-band out of improper contact with the flange 20, when the brakes are not set.

In operating hoisting mechanism in mines or the like, the end of the cable which is 50 connected with the can or bucket ordinarily quickly wears out, necessitating such end of the cable being cut off and the cut end being again attached to the can. This of course shortens the cable, and in order to compensate for this, I have provided the means in-

cluding the clamps 28 and associated elements to retain the surplus amount of the cable upon the outer side of the head 18, whereby when the end of the cable is cut off for the purpose above stated, the clamp 24 70 may be loosened and a suitable amount of the surplus cable fed into the slot 21, subsequently to which the clamp is again tightened up.

When the motor 11 is running, its rotation is imparted to the drum 16, by a clutch, or any other approved means, not shown. The diameter of the bottom wall of the groove 21 being small, upon starting, the cable is pulled slowly, which movement however is quickly accelerated until the cable completely fills the inclined groove 21, at which time the maximum speed of travel of the cable is obtained, the cable then being wound upon the periphery of the drum 16, 80 in any suitable number of layers. I have found that by having a groove 21 inclined inwardly with respect to the longitudinal axis of the drum 16 in alignment with the pulley or sheave 21' (Fig. 7) that the cable 90 is not cut or worn by contact with the edge of the drum 16, upon passing thereon.

The rotation of the drum 16 may be arrested by depressing the brake lever or pedal 42 which swings the crank 40 downwardly and tightens the brake-band, the springs 32 yielding to permit of the proper contraction of the brake-band.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, what I claim is:

1. In hoisting mechanism, a winding drum provided near one end with a cable receiving groove which has a width substantially equal to the diameter of the cable and has a substantial depth so that a plurality of turns of the cable may be arranged therein, said groove being inclined inwardly with relation to its longitudinal axis.

2. In hoisting mechanism, a winding drum provided near its ends with flanges and adjacent one flange with a cable receiving groove which has a width substantially equal to the diameter of the cable and has a substantial depth so that a plurality of turns of the cable may be arranged therein, said groove being inclined inwardly with respect to the longitudinal axis of the drum.

3. In hoisting mechanism, a drum provided with flanged ends and having a groove formed in one end and inclined inwardly with respect to the longitudinal axis of the drum and an opening leading into the

groove and passing to the exterior of such end, a cable passing through the opening and adapted to be wound within the groove and upon the drum, and means to clamp the cable to the exterior of the grooved end of the drum.

4. In hoisting mechanism, a drum provided with flanged ends and having a groove formed in one end and inclined inwardly with respect to the longitudinal axis of the drum and an opening formed in the grooved end and leading into the groove and passing to the exterior of such end, a cable passing through the opening and adapted to be wound within the groove and upon the drum, adjustable means for clamping the cable to the exterior of the grooved

end, and means carried by the exterior surface of the grooved end for receiving surplus cable.

20

5. In hoisting mechanism, a drum provided with a cable receiving groove having a lateral opening adjacent the bottom of the groove for the passage of the cable, and an equalizing wedge arranged within the bottom of the groove adjacent the lateral opening and tapering away from the opening.

25

In testimony whereof I affix my signature in the presence of two witnesses.

HARRY E. JENKINS.
